CINEMATOGRAPHIC FILM AND METHOD

Walter A. Callahan, Burbank, Calif., assignor to
Technicolor Motion Picture Corporation, Holly-
wood, Calif., a corporation of Maine

Application July 31, 1940, Serial No. 348,671

2 Claims. (Cl. 95—5)

In printing motion pictures by imbibition it is customary to use cinematographic matrices comprising picture records in the form of gelatin reliefs which absorb dye in proportion to the depth of the gelatin throughout the different portions of each record, the dye being imbibed by the picture film from the dyed matrix when the two films are pressed together face to face. To prevent the relief records from floating off the film in the etching process it is customary to expose the film through the back so that the exposed portions of the emulsion are next to the film and then to develop the emulsion so that it is less soluble throughout the exposed portions than in the unexposed portions. Thus in etching off the more soluble unexposed portions with warm water each relief record corresponding to the hardened exposed portions is left firmly anchored to the film. Inasmuch as the gelatin is hardened only throughout the picture areas, all the gelatin dissolves off between and outside the sprocket holes along the margins of the film and, in case the matrix has no sound-track, also along the sound-track zone. Thus the matrix film is bare from its edges to the inner ends of the sprocket holes; and in a matrix having no sound-track the bare margin on the sound-track side is still wider.

In dye printing a picture film with a matrix film the two films must be pressed tightly together while in wet condition to bring them into sufficiently intimate contact for the imbibition of dye from the matrix to the other film and inasmuch as it takes several minutes for the migration of the dye the films must be kept in intimate contact for some time. The only practical way to accomplish this is to feed the two films together between pressure rollers and then to rely upon adhesion to hold the films together as they continue along the path in which the dye transfer takes place. However there has always been a tendency for the films to separate along the lateral edges of the picture areas, particularly along the narrower bare margin of the matrix opposite the sound-track margin, after they leave the pressure rollers and before the dye transfer is completed, resulting in faulty transfer along the lateral edges of the pictures.

The present invention is based on the discovery that the aforesaid tendency to separate is due to a deformation of one or both films as they pass between the pressure rollers, namely a sharp bending of one film toward the other film along the aligned edges of the relief records. Usually the margin of the picture film is bent over the

edges of the relief records until the edge of the picture film contacts the bare margin of the matrix film. Thus the sharpness of the bend depends on the width of the bare margin; if the bare margin is narrow the bend is sharp and if the bare margin is wide the bend is not so sharp. Consequently the deformation is less along the side of the matrix which is bare in the sound-track zone as well as between and outside the sprocket holes.

If the aforesaid deformation is sharp enough to give the picture film a more or less permanent set a slight arch remains in the picture film after it leaves the aforesaid pressure rollers and, as the bent margin swings back more or less toward its normal plane after leaving the rollers, the films tend to pull apart along the edges of the relief records due to the aforesaid arch. In the case of a matrix having no sound-track the deformation along the sound-track side is usually not great enough to cause much trouble, but in the case of bare margins which are narrow the aforesaid arching seriously interferes with dye transfer along the edges of the picture.

According to the present invention the margin of the matrix film is exposed so that the processing which hardens the picture areas throughout the exposed or non-exposed portions also hardens the margin of the coating of gelatin or the like throughout the corresponding portions. Thus in the etching process a shim of gelatin is left along the margin of the film, the shim serving to prevent the aforesaid marginal bending and resulting deformation. When using the type of processing in which the exposed portions are rendered less soluble than the unexposed portions, the exposure of both picture areas and margin are effected by light transmitted through the back of the film. Either one or both margins of the film may be exposed depending upon particular requirements. The degree of exposure of the margin or margins preferably approximates the average exposure of the picture areas so that the average thickness of the relief records approximates that of the shim or shims. It will be understood of course that the margins may be exposed with any suitable light, preferably light of the same spectral quality as that used in printing the pictures.

For the purpose of illustration a typical embodiment of the invention is shown in the accompanying drawing in which:

Fig. 1 is a diagram indicating the successive steps of the method;

Fig. 2 is a side elevation partly in section of apparatus for exposing the margins of a film;

Fig. 3 is a section on line 3—3 of Fig. 2;

Fig. 4 is a section on line 4—4 of Fig. 2;

Fig. 5 is a top plan view of apparatus for applying hardening solution to the margins of a film; and

Fig. 6 is a side elevation of the apparatus shown in Fig. 5.

The particular embodiment of the invention chosen for the purpose of illustration comprises a picture film P which is printed by imbibition from a matrix film M (bottom of Fig. 1), the picture film comprising the usual transparent backing 1 and a coating of gelatin 2 into which the dye migrates from the relief records 3 on the transparent backing 4 of the matrix. In the matrix shown in the drawing the position of the sound-track zone is indicated at 5 without any track in the zone. As shown at the top of Fig. 1 the pictures are printed in the areas 6 and the margins of the film are exposed from the edges inwardly to the lines 8 at the outer ends of the sprocket holes. As indicated in the diagram these two exposures may be effected either at the same time or consecutively, and if printed consecutively either the pictures or the margins may be printed first. If the film is printed through the back it is developed with a developer which hardens the gelatin throughout the exposed portions while leaving the gelatin throughout the unexposed portions relatively soluble. After being developed the film is etched in warm water, leaving the picture records 3 in relief and leaving shims 8 of gelatin adhering to the film along the margins. In the etching process all of the gelatin is removed in the unexposed regions, as indicated by the unstippled areas in Fig. 1, and the reduction in thickness of the gelatin, if any, is uniform throughout the marginal areas because the preliminary exposure is uniform throughout these areas. Following the etching step the marginal shims may be further hardened, as indicated in the third rectangle of Fig. 1, by applying hardening solution to the marginal portions of the film as hereinafter described. This not only serves to increase the resistance of the shims to wear but it also tends to prevent absorption of dye by the shims. After the matrix has been thus completed it is soaked in dye of the appropriate kind and color, then rinsed, and then pressed against the film to be printed by imbibition as indicated at the bottom of Fig. 1. As mentioned above the film P to be printed is first wet to soften the gelatin coating after which the two films are rolled together face to face to squeeze out all intervening air and superficial liquid, thereby to cause the wet films to adhere together long enough for the dye to migrate from the matrix to the other film. By virtue of the shims 8 the margins of the film P cannot be bent down over the lateral edges of the relief records 3, thereby avoiding the aforesaid arching and faulty transfer along the lateral edges of the pictures.

While the margins of the film may be exposed in any one of various ways, typical means is illustrated in Figs. 2, 3 and 4 where M designates the aforesaid matrix, 11 a light housing containing a lamp 12 for exposing the margins of the matrix through the slots 13. The film may be fed continuously through the passageway 14 between the rear wall 15 of the housing 11 and the film gate 16.

10 One of the various ways of additionally hardening the shims 8 is shown in Figs. 5 and 6 where 21 are soft brushes which wipe the margins of the film M as it passes to the roller 22. The brushes 21 are mounted in the lower ends of inclined tubes 23 which may be supplied with hardening solutions through flexible tubes 24 leading from a suitable reservoir. The tubes 23 are mounted in a clamp 25 which is supported by a suitable bracket 26. Of the various solutions suitable for use in hardening the marginal shims the following are recommended: an approximately 10% solution of aluminum chloride followed by a rinse in dilute ammonia, or ferric chloride (10% in 50% alcohol) followed by a dilute ammonia rinse.

25 It should be understood that the present disclosure is for the purpose of illustration only and that this invention includes all modifications and equivalents which fall within the scope of the appended claims.

30 I claim:

1. The method of processing motion picture film to produce picture records in relief, which comprises exposing the picture areas of the film to the images to be recorded, exposing the margin of the film between the sprocket holes and the edge of the film to light, developing the film to render the exposed and non-exposed portions of the gelatin differentially soluble, etching off the more soluble gelatin to leave not only the records 40 in relief but also a layer of gelatin along said margin, and then hardening said marginal layer to reduce its dye absorptivity and to increase its resistance to wear without correspondingly hardening the picture area.

45 2. The method of printing a motion picture film by imbibition from a matrix film, which comprises exposing the picture areas of the matrix film to the images to be recorded, exposing the margin of the matrix film with light, developing the matrix film to render the exposed and non-exposed portions of the gelatin differentially soluble, etching off the more soluble gelatin to leave not only the records in relief but also a layer of gelatin along said margin, then 50 hardening said marginal layer to reduce its dye absorptivity and to increase its resistance to wear without correspondingly hardening the picture area, dyeing the matrix film, and pressing the two films together to print by imbibition, said marginal layer of gelatin serving to hold said margin from bending toward the other film when the two films are pressed together.
